UNITED STATES PATENT OFFICE.

EDWARD A. FARR, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A TRAY OR SIMILAR ARTICLE.

Application filed December 17, 1925. Serial No. 15,774. Term of patent 7 years.

To all whom it may concern:

Be it known that I, EDWARD A. FARR, a citizen of the United States, residing at Meriden, in the county of New Haven, State of Connecticut, have invented a new, original, and ornamental Design for a Tray or Similar Article, of which the following is a specification, reference being had to the accompanying drawing, forming a part thereof.

Figure 1 is a plan view of the tray showing my new design.

Fig. 2 is a side elevation of the same.

I claim:

The ornamental design for a tray or similar article substantially as shown.

EDWARD A. FARR.
